UNITED STATES PATENT OFFICE.

CLINTON R. BOONE, OF LARCHMONT, NEW YORK.

LIGHTER.

Application filed April 25, 1927. Serial No. 186,395.

This invention relates to improvements in lighters and has particular reference to a cigar and cigarette lighter for producing a flame upon the actuation of a pull chain.

One of the primary objects of the invention resides in a lighter which includes a base by which the device may be supported, and which base also serves as an ash tray, thus rendering the same useful for two different purposes. The device may be set upon a table or desk and will be found most useful in clubs, restaurants, public smoking rooms, homes and like places.

Another object of the invention is to provide a lighter of the type embodying a container having a wick extended therefrom and which is adapted to contain a volatile fuel such as benzine, gasoline, or the like, and which is lighted by a spark produced by contact of a friction wheel with a flint stick, the wheel being actuated to turn in one direction upon the pulling on the chain, and idle upon the release of the chain, to prevent waste of the flint.

Another object of the invention is to provide a novel form of actuating means, which includes a segmental cover member normally held in a position over the wick but which is rapidly moved to an open position by the building up of a force or tension which overcomes the means for normally holding the segmental cover member in a closed position, and which rapid movement is necessary to the actuation of the friction wheel to produce the spark from which the wick is lighted.

A still further object is the provision of a combination lighter and ash tray which is simple and inexpensive of construction, positive of operation, and attractive in appearance.

With these and other objects in view, the invention resides in certain novel construction and combination and arrangement of parts, the essential features of which are hereinafter fully described, are particularly pointed out in the appended claims, and are illustrated in the accompanying drawings, in which:

Figure 1 is a perspective view of my improved lighter.

Figure 2 is a vertical sectional view therethrough.

Figures 3 and 4 are detail views showing the different positions of the parts during operation.

Figure 5 is a vertical transverse sectional view on the line 5—5 of Figure 2.

Figure 6 is a detail perspective view of the ratchet friction wheel and its actuating member.

Referring more particularly to the drawing, the reference numeral 10 designates my improved lighter in its entirety and which includes a base 11 in the form of an ash tray and from which a post 12 rises centrally therefrom for supporting a hollow post or container 13 which container tapers to a reduced neck 14. The container 13 is held in a position by a threaded stud 15 which extends from the bottom thereof and which passes through an opening in the top of the post to receive a retaining nut 16.

Supported upon the top of the container 13 is a platform 17 having a tube 18 extending from the underside thereof and which tube fits into the neck 14 and frictionally engages the inner walls thereof. A wick 19 extends upward through the tube for exposure above the platform, and which wick is submerged in the volatile liquid such as benzine, or gasoline to be stored in the container. The platform 17 and wick are removable from the container as a unit to permit of the filling of the container with fuel through the wick 14.

The platform 17 extends outwardly from the container and has two diametrically opposed ears 20 bent from the sides thereof and which serve as a bearing for a shaft or pin 21. Pivotally mounted on the ends of the pin beyond the ears, is a segmental cover member 22 which rests upon a flange or seat 23 rising from the platform 17 and which partially surrounds the exposed end of the wick. The member 22 also has a snuffer cap 24 for receiving the exposed end of the wick to snuff out the flame upon the closing of the same. Attached to the forward end of the segmental member is one end of a flexible pull chain 25 which chain passes over a pin or bar 26 which bridges the side walls of the segmental cover but which pin is normally disposed just out of vertical alignment with the axis of the shaft 21 when the segmental cover member is in a closed position.

The free end of the chain hangs vertically beside the container and has a tension device 27 provided in the length thereof and which is interposed between the segmental cover member and the free end of the chain. The tension device comprises a

tubular casing 28 having a closed end to which the section A of the pull chain 25 is connected. The other end of the casing 28 is closed by a removable plug 29 through 5 which a wire or rod 30 extends and which rod has its outer end fastened to the chain section B of the pull chain.

The inner end of the rod has a head or piston 31 thereon which is normally held 10 adjacent the top of the cylinder or casing by an expansible spring 32 for the purpose to be presently described.

Depending from the platform 17 and in vertical alignment with the axis of the shaft 15 21 is a tubular casing 33 having an adjusting screw 34 in its lower end for varying the tension of an expansible spring 35 which spring acts against a flint stick 36 to force the stick against the friction spark wheel 37 20 which is rotatably mounted on the shaft 21. One of the side faces of the spark wheel is provided with ratchet teeth 38 for engagement by a tooth 39 provided on a dog or pawl 40 fixed to the segmental cover member 25 whereby said flint wheel is rotated a predetermined distance on each movement of the segmental cover member to an open position, but which wheel remains idle upon the movement of the cover member to a closed position. 30 During the rotation of the friction wheel, a jump spark is produced which serves to ignite the wick as will be readily appreciated. A coil spring 41 encircles the shaft 21 and is interposed between the ratchet friction wheel 37 and one of the adjacent gears 20 to maintain the wheel in operative relation to the pawl 39 and which spring permits a lateral sliding movement of the wheel when the pawl returns to a normal position 35 40 after having actuated the friction wheel in one direction. The spring 41 also acts to return the segmental cover member to a normal or closed position and has one of its ends extended as at 42 and anchored to the 45 platform, while the other end of the spring is extended as at 43 and bears against the pin or bar 26.

In operation, the operator grasps the section B of the pull chain and by exerting a 50 pull thereon, a force is built up by reason of the compression of the spring 32 until the segmental member is upset to a point where it will impart a rapid movement thereto and which action takes place after the cover has 55 moved over a predetermined distance. At the beginning of the pull, the force is exerted upon the fulcrum point provided by the pin 26 and the pull remains there until the segmental cover reaches a predetermined 60 point in its open movement, whereupon the action of the spring 32 produces the desired result. During the movement of the segmental cover to an open position, a spark is produced in a manner just described and each 65 spark ignites the exposed end of the wick.

From actual experience, it has been found necessary to employ a spring such as shown in 38 within the length of the pull chain in order to assure of the successful operation of this invention. It is imperative that the 70 cover be actuated by a quick movement to produce the desired spark and the force built up by the compression of the spring 32 upon the pulling on the chain becomes one of the leading factors to the success of the operation 75 of the device. This desired quick movement can not be obtained by merely pulling upon a continuous length of chain as experiments have proven that without the spring it will not operate successfully. 80

From the foregoing description, it will be seen that I have provided a novel form of lighter which may also be used as an ash tray and the same will be found most useful in such places where smoking is permitted. The device is inexpensive of manufacture due to its simplicity and will add to the furnishings of a room rather than detract therefrom which has been the objection in the present style of lighters. The device is also positive in operation so that an operator will not feel that he is compelled to actuate the device several times before producing a flame. 85

While I have described what I deem to be the most desirable embodiment of my invention, it is obvious that many of the details may be varied without in any way departing from the spirit of my invention, and I therefore do not limit myself to the exact 90 details of construction herein set forth nor to anything less than the whole of my invention limited only by the appended claims. 95

What is claimed as new is:—

1. A lighter comprising a base, a fuel container rising from said base, a platform supported upon the top of said container, a wick extending from said container onto said platform, a flint stick rising above said platform and disposed adjacent said wick, a rotatable friction wheel engaging said flint stick, a segmental cover member pivotally mounted on said platform and normally covering the exposed end of said wick, friction wheel actuating means operable upon movement of said segmental cover member, a flexible actuating element of two sections, one of said sections having one of its ends fixedly attached to said segmental cover member, and tension means connected to the adjacent ends of the sections of said flexible element, substantially as and for the purpose specified.

2. A lighter comprising a base, a fuel container rising from said base, a platform supported upon the top of said container, a wick extending from said container onto said platform, a flint stick rising above said platform and disposed adjacent said wick, a rotatable friction wheel engaging said flint

- stick, a segmental cover member pivotally mounted on said platform and normally covering the exposed end of said wick, friction wheel actuating means operable upon movement of said segmental cover member, a flexible actuating element of two sections, one of said sections having one of its ends fixedly attached to said segmental cover member, means for normally holding said segmental cover member in a closed position, and a compressible element connected to the adjacent ends of the sections of said flexible actuating member and adapted to be compressed upon the pulling upon the extreme end of said flexible element to build up a force to overcome said means to quickly upset said segmental cover member to an open position and simultaneously cause the rapid movement of said friction wheel.
- 20 3. A lighter comprising a base, a container rising from said base, a platform having a tube extending from the underside of said base and frictionally engaging the walls of said container, a wick extending through said tube and having one of its ends exposed above said platform and its other end depending into said container, a flint stick extending above the surface of said platform, a friction wheel journalled for rotation upon said platform, and actuating means for imparting a rotary movement to said friction wheel in one direction.
- 25 4. A lighter comprising a base, a container rising from said base, a platform supported upon said container, a wick rising from the interior of said container and having one end exposed above said platform, a segmental cover member pivotally mounted upon said platform, means for normally holding
- 20 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means.
- 25 5. A lighter comprising a base, a container rising from said base, a platform supported upon said container, a wick rising from the interior of said container and having one end exposed above said platform, a segmental cover member pivotally mounted upon said platform, means for normally holding
- 30 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means.
- 35 6. A lighter comprising a base, a container rising from said base, a platform supported upon said container, a wick rising from the interior of said container and having one end exposed above said platform, a segmental cover member pivotally mounted upon said platform, means for normally holding
- 40 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means.
- 45 7. A lighter comprising a base, a container rising from said base, a platform supported upon said container, a wick rising from the interior of said container and having one end exposed above said platform, a segmental cover member pivotally mounted upon said platform, means for normally holding
- 50 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means.
- 55 8. A lighter comprising a base, a container rising from said base, a platform supported upon said container, a wick rising from the interior of said container and having one end exposed above said platform, a segmental cover member pivotally mounted upon said platform, means for normally holding
- 60 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means.
- 65 9. A lighter comprising a base, a container rising from said base, a platform supported upon said container, a wick rising from the interior of said container and having one end exposed above said platform, a segmental cover member pivotally mounted upon said platform, means for normally holding
- 70 said segmental cover member in a closed position, a flint stick extending above said platform, a friction wheel journalled above said platform and engageable with said friction stick, a pull chain having one of its ends fixed to the forward end of said segmental cover and its other end passing over a bar and depending vertically beside said container, and co-acting means between said segmental cover and said friction wheel for imparting a partial rotation thereto upon applying a downward force to said pull chain against the actuation of said first means, and a compressible spring arranged in said pull chain intermediate its ends.
- 75 In testimony whereof I have affixed my signature.

CLINTON R. BOONE.
